UNITED STATES PATENT OFFICE.

HARRIE A. BALLARD, OF BOSTON, MASSACHUSETTS, ASSIGNOR TO THE BOYLSTON MANUFACTURING COMPANY, OF SOUTH BOSTON, MASSACHUSETTS, A CORPORATION OF NEW JERSEY.

MACHINE FOR INSERTING FASTENERS.

1,108,421.

Specification of Letters Patent.

Patented Aug. 25, 1914.

Application filed January 28, 1909. Serial No. 474,668.

To all whom it may concern:

Be it known that I, HARRIE A. BALLARD, of Boston, in the county of Suffolk and State of Massachusetts, have invented certain new and useful Improvements in Machines for Inserting Fasteners, of which the following is a specification.

This invention relates to machines for driving fasteners such as tacks used in the manufacture of shoes.

The chief feature of the invention lies in the tack feeding mechanism by which the tacks are fed one by one from a race into a delivery throat through which a driver passes. In machines of this type it is desirable that the tack occupying the throat should be supported therein until such time as the driver descends to drive it into the work. The tack is, in some machines, supported by the tack-pick which underlies the head of the tack, and which is adapted to be displaced. In this case the usual manner of displacing the pick is by means of the head of the driven tack which engages a beveled edge formed thereon. This method is objectionable in that the pick is subjected to very severe blows and wear, and becomes useless for the purpose after comparatively little usage. The usual manner of controlling a machine of this type is to cause it to stop when the delivery throat is in the line of the driver and with a tack occupying the throat. In such case the order of operations is as follows:—first, driving of the tack and return of the driver, then relative movement of the pick and race in order to place another tack in the throat, and occupancy of the throat by some tack-supporting member until displaced by the action of the driver.

According to the present invention the delivery throat is farthest from the line of the driver when the machine is at a state of rest and the order of movements is as follows:—first, relative movement of the pick and race for the purpose of feeding a tack into the initially unoccupied throat, then retraction of the pick in a line transverse to the feeding movement, and then projection and retraction of the driver.

The chief object of this invention is to support the tack by means of a retractive pick until the instant when the driver starts, and to provide means for retracting the

pick at this instant, before the tack is engaged by the driver. 55

Other features of the invention are hereinafter described and claimed, and are illustrated upon the accompanying drawings which show one form in which the invention may be embodied. 60

Figure 1 represents a front elevation of this invention. Fig. 2 represents a top plan view of the tack-feeding mechanism in one position. Fig. 3 represents a similar plan view of another position. Fig. 4 represents a longitudinal section of the delivery end of the race, with a tack pick corresponding in position to Fig. 2. Fig. 5 is a view similar to Fig. 4 but corresponding in position to that of Fig. 3. Fig. 6 represents a transverse section of the whole machine. Figs. 7 and 8 represent respectively a side elevation and front elevation of the tack-feeding mechanism. Fig. 9 represents a section similar to Fig. 4 with the addition of a series of tacks. Figs. 10 and 11 are horizontal sections of the tack-feeding mechanism and correspond in position to Figs. 2 and 3 respectively. 80

The same reference characters indicate the same parts wherever they occur.

The essential parts of the machine are the frame 12, power shaft 13, tack-race 14, a tack retainer 15, tack pick 16, driver 17, 85 tack reservoir 18 and tack elevator 19. One end of the race is filled with tacks *a* by the elevator, and the other end terminates in a delivery throat 20 through which the driver 17 is projected. An aperture 21, extending laterally through the delivery end of the race, is formed for the reception of the tack-pick, and the tacks are advanced one by one into the throat 20 by transverse movement of the race or pick, one with relation to the other. In this form of machine the race is moved and the pick is stationary except as hereinafter specified. One wall 22 of the aperture is on a line intersecting the throat and constitutes a stop for positioning the 90 pick and retainer. 95

The two members 15 and 16 are affixed to arms 23 and 24 which, together with a rod 25 on which they are affixed, constitute an oscillatory hanger. The rod extends transversely of the race and is mounted in bearings formed in a bracket 26 affixed to the frame 12. The rod is installed so as to be 105

movable endwise and also about its axis, but is normally held in one position by a spring 27 which tends to move it both along and about its axis. The spring is connected to the hanger by means of a radial pin or arm 28 and to a fixed pin 29 in the bracket. The limit of axial movement of the hanger is determined by the bearing 30 which acts as a stop for the arm 28, while the limit of rotary motion is determined by the wall 22 in the tack-race.

The upper end of the race 14 is secured in the tack-reservoir 18 and is supported thereby. The reservoir is mounted on trunnions 31 about which it is adapted to oscillate. The reservoir is provided with an arm 32 carrying a roll 33 which occupies the groove of a cam 34 affixed on the shaft 13. By means of the cam the reservoir and race are oscillated so as to move the throat 20 to and from alinement with the driver 17. The cam 34 is so formed as to be of no effect while the driver 17 is in the throat. Lateral movement of the race is caused to impart movement of the pick longitudinally of the race by means of a lever 35 having the characteristics of a cam. Said lever (see Figs. 2, 3 and 7) is mounted on the bracket 26 by means of a fulcrum 36. One end of the lever 30 has a finger 37 which is confined between the race and a strap 38 affixed thereon, in a manner similar to a pin and slot connection. The other end of the lever has a straight edge 39 and an inclined edge 40 adjoining it, both of which are adapted to engage the arm or pin 28 of the tack-pick hanger. When the throat of the race is farthest from the path of the driver (Figs. 2 and 10) the edges 39 and 40 of the lever 35 are disengaged from the pin 28. In this position the pick is held by the spring 27 in a line intersecting the throat 20, (see Figs. 4 and 9) but when the throat is moved into alinement with the driver (Figs. 1, 3, 8 and 11), the inclined edge 39 strikes and moves the pin 28 and so displaces the pick from the throat. The adjacent ends of the complementary members 15 and 16 are inclined and arranged so as to engage the shank of the foremost tack in the race and advance it into the throat. The tack (see Fig. 9) after being advanced to the throat drops until its head engages the foremost edge of the member 16, which is cut back very slightly, as shown in Fig. 10, at b. At this time the inclined edge 40 strikes the pin 28, thereby retracting the pick. It is preferable that when the race comes to a state of rest with the throat in alinement with the driver, the pick should be clear of the throat but still as close to it as possible, (see Fig. 11), the pin 28 should be at the point where the edges 39 and 40 meet, (see Fig. 3), and the driver should start to descend.

65 The driver here shown is the type which is

actuated in one direction by a spring 41, and in the other direction by a segmental piece 42 which revolves with the shaft 13 and engages a block 43 on the driver bar 44.

If, through any defect in a tack or in the 70 operation of the tack-feeding mechanism, a tack should stick or become dislodged in the pick, the pick would be able to move laterally with the race and so avoid the liability of becoming bent or broken. In this case 75 the rod 25 of the pick hanger would be moved axially in its bearings against the tension of the spring 27. Such movement of the pick would in no wise affect the angular position to which the pick is retracted 80 because the straight edge 39 is parallel to the axis of the rod 25 when the race is moved to driving position.

The elevator 19, which deposits tacks in the upper end of the race, is cylindrical in 85 form and has a hub 45 which is mounted on a transverse shaft 46. One side of the elevator is open and surrounds an annular flange 47 on the reservoir so loosely as to permit the aforesaid oscillation of the reservoir. The reservoir is also open at this point so that the contents may be enabled to gravitate into the elevator. The elevator is formed with a circular series of internal buckets 48 and it is revolved so as to cause 95 the buckets to elevate the tacks and discharge them upon the upper end of the race. For revolving the elevator it is provided with an external gear 49 which is driven by a pinion 50 on one end of a transverse shaft 51. The shaft extends through a bearing 52 on the frame 12 and has on its other end two collars 53. Between the collars is a worm gear 55 and a helical spring 54. The gear 55 is driven by a worm 56 on 100 the shaft 13, and imparts movement to the shaft 51 by means of the frictional connection due to the spring 54. The elevator is provided with another gear 57 which may be employed to drive a stripper for removing the excess tacks from the race. 105

Having thus explained the nature of my said invention and described a way of constructing and using the same, although without attempting to set forth all of the forms in which it may be made or all of the modes of its use, I declare that what I claim is:—

1. A machine of the character described comprising picking means movable about an axis and movable lengthwise of said axis, a tack-delivering device and means for effecting a relative reciprocation of said device and said picking means.

2. A machine of the character described comprising picking means movable about an axis and movable lengthwise of the axis, a stop for limiting rotary movement, a stop for limiting lengthwise movement, yielding means for holding the picking means normally against both stops, a tack-deliver- 125

ing device and means for effecting relative reciprocation of said picking means and said tack-delivering device.

3. A machine of the character described comprising a tack race, a pick arranged transversely of the race, means for effecting a relative movement of the race and pick transversely of the race to separate the end tack in the race, means for mounting said pick to move about an axis transverse to the tack race, and means for moving said pick about said axis to release a separated tack.

4. A machine of the character described comprising a tack race, a driver, and a tack pick movable about an axis extending transversely of the race and driver and movable lengthwise of said axis.

5. A machine of the character described comprising a movable tack pick, a movable tack race for supporting a tack in position to be fed by the pick, and means actuated by the race for moving the pick.

6. A machine of the character described comprising a tack pick movable in directions transverse to each other, a movable tack race for supporting a tack in position to be fed by the pick, and means actuated by the race for moving the pick in one of said directions.

30 7. A machine of the character described comprising a tack pick movable in transverse directions, a stop for limiting movement in one direction, a tack race, a stop on the race for limiting movement of the pick 95 in its transverse direction, yielding means for holding the pick in normal position, and means actuated by the race for moving the pick in one direction.

8. A machine of the character described comprising a tack race and tack pick, one movable relatively to the other for feeding a tack, said pick being otherwise movable transversely of the feeding movement, and actuating mechanism for causing, first, a feeding movement, then a movement of the pick transverse to the direction of the feed, retrograde transverse movement of the pick, and retrograde feeding movement.

9. A machine of the character described comprising tack driving devices, a driver, a tack race having a delivery throat, a tack pick adapted by relative movement of itself and the race to feed a tack and to support it in the throat, said pick being otherwise movable for releasing the tack in the throat, and actuating means independent of the driving devices for causing first, the feeding of a tack, then a retraction of the pick from the tack, then movement of the driver, retrograde retractive movement of the pick, and retrograde feeding movement.

10. A machine of the character described comprising a driver, an initially distant tack race movable to and from the path of the driver for feeding a tack, a throat in the

race, a retractive tack pick adapted to cooperate with the race to feed a tack into the throat and support it there, and means for retracting the pick from the tack at the end of the feeding movement.

70 11. A machine of the character described comprising a tack-race, a tack-pick, one movable relatively to the other, and means actuated by the picking movement of the race and pick for moving the pick transversely of said picking movement.

75 12. A machine of the character described comprising a tack-race, a tack-pick, said race and pick being relatively movable, and means actuated by transverse movement of one relatively to the other for moving the pick longitudinally of the race.

80 13. A machine of the character described comprising a tack-race, a tack-pick, one movable relatively to the other, a transverse face in the race, yielding means for supporting the pick against said face, and means actuated by transverse relative movement of the race and pick for retracting the pick from said face.

85 14. A machine of the character described comprising a tack race, picking means movable both longitudinally and transversely of the race, a stop for limiting longitudinal movement, a stop for limiting transverse movement, and yielding means for holding the picking means normally against both stops.

90 15. A machine of the character described comprising a tack reservoir and a tack elevator coöperating to form a tack chamber, and a tack race affixed to said reservoir in position to receive tacks from the elevator, said elevator being movable about an axis, and said reservoir and race being otherwise movable as one, in combination with a tack pick, and power-actuated means for moving said tack race and reservoir relatively to said pick to cause the separation of a tack by the pick.

of the driving devices and of the tack being driven to cause said pick to release such tack.

18. A machine of the character described comprising a tack-race and a tack-pick, one movable relatively to the other for feeding tacks, and means operable during the tack-picking movement for moving said pick to release the tack during the latter part of the picking movement.

19. A machine of the character described comprising a tack reservoir, a tack-race rigidly supported by said reservoir, and a tack elevator coöperating with said reservoir to form a tack chamber, said elevator being movable about an axis, and said reservoir and race being movable about an axis substantially transverse to the elevator axis, said elevator and race being so related that the one is adapted to discharge tacks upon the other, in combination with a tack pick, and power-actuated means for moving said tack race and reservoir relatively to said pick to cause the separation of a tack by the pick.

20. A machine of the character described comprising a tack-race and a tack-pick, one movable relatively to the other, means for causing relative movement thereof to separate a tack, and means operative by such relative movement for causing the pick to release the separated tack.

21. A machine of the character described comprising a tack elevator and a tack reservoir coöperating to form a tack chamber, said elevator being movable about an axis and having a circular opening concentric to said axis, said reservoir having a discharge mouth arranged in said opening, and a tack race supported by said reservoir in position to receive tacks from said elevator, said reservoir and race being movable about another axis.

In testimony whereof I have affixed my signature, in presence of two witnesses.

HARRIE A. BALLARD.
